Attorney.

UNITED STATES PATENT OFFICE.

JOSEPH P. BAUMGARTNER, OF PHILADELPHIA, PENNSYLVANIA.

SUSPENDED-GARTER ADJUSTMENT.

1,317,676.

Specification of Letters Patent.

Patented Oct. 7, 1919.

Application filed February 12, 1919. Serial No. 276,475.

To all whom it may concern:

Be it known that I, JOSEPH P. BAUMGARTNER, a citizen of the United States, residing at Philadelphia, in the county of 5 Philadelphia and State of Pennsylvania, have invented a certain new and useful Suspended-Garter Adjustment, of which the following is a specification.

My invention relates to buckles for adjustment of the length of a garter-supporting strap or other suspender.

The purpose of my invention is to provide for release of the catch by pressure upon the sides of the buckle against the body of 15 the wearer, facilitating single hand movement and permitting particularly flat, compact and attractive formation of the parts.

A further purpose is to provide an outwardly-pressing spring catch gripping the 20 fabric near the sides.

A further purpose is to protect a spring catch from excessive releasing movement.

Further purposes will appear in the specification and in the claims thereof.

I have preferred to illustrate my invention by but one form, selecting a form which I have found in use to be practical, efficient, reliable and very attractive in appearance and which at the same time well illustrates 30 the principles of my invention.

Figure 1 is a broken front elevation, showing my invention applied to a fabric strap to be adjusted.

Fig. 2 is a rear elevation of the construction seen in Fig. 1.

Fig. 3 is a side elevation of the structure seen in Fig. 1, with the addition of the lower part of the strap.

Figs. 4, 5, 6 and 7 are sections of Figs. 1 40 and 2, taken upon lines 4—4, 5—5, 6—6 and 7—7 respectively.

Figs. 8 and 9 are perspective views of the two parts of my buckle.

Fig. 10 is an end elevation of the frame 45 shown in Fig. 8.

In the drawings similar numerals indicate like parts.

The buckle comprises two metallic members, the frame 10 and the spring pronged 50 catch 11, secured together by rivet 12.

The frame comprises a central plate 13, slotted or slotted and rearwardly pressed at one end, at 14, to form a bar 15 preferably far enough behind the plate for the end of 55 the fabric strap to lie between, and to be secured to the bar 15, as by sewing. At its

opposite end the sides of the plate portion are extended and are bent rearwardly and then toward each other to form fingers 16 and 16' far enough back of the plate 13 to 60 form, between the fingers and the plate, a longitudinally extending passage 17 for the strap to be adjusted, holding flat the end which is secured to the bar 15.

The reasons for the rearward position of 65 the bar 15 and of the fingers 16 and 16' are to remove the securing means for the end of the strap from friction engagement by the intermediate (front) strap section and to give finish to the buckle. 70

At a convenient part, preferably in the middle of the plate, between the bar 15 and the fingers 16, 16', the sides of the plate are extended forwardly and then turned toward each other at 18, 18' to form a passage 19 between the plate and these forward extensions, through which passage the adjustable intermediate (front) part of the fabric strap is passed. 75

Between these points the strap is formed 80 into a loop, as at 20, for the support of any suitable garment fastening device shown at 21.

The catch 11 is of spring material and is balanced on opposite ends so as to grip at 85 both sides of the strap. It comprises an intermediate spring strip 22 on each side of the center, which may be narrow, as shown, but in that case is laterally extended, as at 23, at each end to support spaced grips, 90 here shown as prongs 24. These are normally sprung forward from the rear side of the front (intermediate) fabric section 25. With the wide plate shown, the plate is notched at 13' to give room for the movement of the prong, the plate between the prongs giving support to one of the prongs at each side against strain longitudinally of the fabric strip. 95

The ends of the spring catch are forwardly extended, as at 26, 26' so that they can be engaged by the thumb and finger of the wearer and pressed rearwardly against the resistance of the body. As this resistance will be most firm at the middle 27, 100 where it comes most solidly against the body 28 the two ends 26, 26' will be sprung toward the body, relatively withdrawing the prongs from the rear of intermediate section 25 of the strip and permitting movement of the strip to any position before the finger and thumb pressure against the ends 105 110

of the catch is relieved to permit the prongs to engage the strip at new points.

In order to prevent excessive rearward movement of the ends 26, 26', by reason of which the spring catch might be bent out of shape, the ends 26 and 26' are projected toward each other to form fingers 29 and the plate is extended at each side, in the form of stops 30, to be engaged by the fingers 29, preventing excessive rearward movement of the catch ends. This protects the spring from distortion. A little space is allowed at 31 between the stops 30 and the forward extensions of the catch, so as to allow a little side movement in assembling the parts. This provides for placing the catch without distortion of its extensions.

The front members 18 and 18' are apertured, as at 32 to give room for convenient riveting of the parts. It will be obvious that any form of attachment may be used to secure the parts together, so that the grips will normally spring into the front passage and may be pressed rearwardly by means of the ends of the catch so as to release the grips from the fabric.

While showing the best form of my invention known to me, as required by the statute, I recognize that many variations may be made in my invention without departing from the spirit and scope thereof. It is my intention to include all such within my claims.

Having thus described my invention, what I claim as new and desire to secure by Letters Patent is:

1. A buckle comprising a frame having side edges extended and turned toward each other to form with the plate a passage, in combination with a pronged spring catch secured at its middle part to the plate outside the passage, leaving its ends free, extending from side to side of the passage and normally pressing its prongs across the passage near the sides thereof.

2. A buckle comprising a frame providing a longitudinally-extending passage for a fabric strip, in combination with a spring catch secured near its middle portion to the frame and having free ends carrying fabric-engaging grips located at the sides of the passage and normally pressing the grips across the passage, and hand-operated releasing members connected with the ends

and effective to move the grips out of the passage.

3. A buckle comprising a frame providing a longitudinally-extending fabric passage, a catch secured near its middle portion to the frame and having its ends of spring material and adapted to extend in a direction across the passage for gripping purposes and means upon the ends engaged by the hand of the user to release the catch.

4. A buckle comprising a frame having a longitudinally-extending fabric passage, and a catch secured at its middle part to the frame back of the passage, having a fabric-engaging grip near each end, adapted to be supported by the frame against strain longitudinally of the passage, the catch being provided with operating end portions for release movement of the grips out of the passage.

5. In a buckle, a frame comprising a central plate member extended at its edges rearwardly and toward each other to form a rear passage and forwardly and toward each other to provide a front passage in combination with a spring catch secured at its middle part to the back of the plate member, extending toward the edges of the passage and carrying grips spring-pressed to enter the front passage.

6. In a buckle, a frame comprising a central plate member extended at its edges rearwardly and toward each other to form a rear passage and forwardly and toward each other to provide a front passage in combination with a spring catch secured at its middle part to the back of the plate member, extending toward the edges of the passage, carrying grips spring-pressed to enter the front passage and having terminals for engagement by the wearer to release the grips.

7. A buckle comprising a metal frame having a longitudinally-extending fabric passage and a catch secured in its middle portion to the frame back of the passage, having a fabric engaging grip near each end, spring pressed across the passage and having terminals for hand operation, the terminals being extended toward each other to engage the metal of the frame to limit the release movement of the spring grips.

JOSEPH P. BAUMGARTNER.
